UNITED STATES PATENT OFFICE

2,394,053

GRINDING MILL

John R. Hall, Chicago, Ill., assignor to International Harvester Company, a corporation of New Jersey

Application November 22, 1943, Serial No. 511,259

1 Claim. (Cl. 241—245)

This invention relates to a new and improved grinding mill and has for one of its principal objects the provision of means for delivering ground material.

An important object of the invention is to provide a plate-grinding mill having its rotating plate carrying paddles for delivering the ground material to a vertical elevator.

Another important object of the invention is to provide a housing enclosed plate mill capable of grinding material and delivering it to the top of the housing smoothly and continuously with a minimum number of operating parts.

Other and further important objects of this invention will become apparent from the following specification and accompanying drawing, in which:

Figure 1 is a side elevation of the plate-grinding mill of this invention partly in section;

Figure 2 is a sectional view taken on the line 20 2—2 of Figure 1; and

Figure 3 is a detail view of the grinding plates of the subject invention, shown partly in section.

As shown in the drawing, reference numeral 6 indicates generally a base on which is mounted a housing 7 substantially rectangular in shape and having a discharge spout 8 projecting from the top and side thereof, as best shown in Figures 1 and 2.

Figure 2 depicts a flat belt cylinder pulley 9, which is adapted to be driven from a tractor having a power take-off or any other suitable driving means. The pulley 9 is integral with a main shaft 11, which acts to rotate a plate 12, one of a pair of grinding plates. The rotating plate 12 cooperates with a stationary plate 13, as best shown in Figure 3, to grind material being fed to a V-shaped slot 14 between the plates 12 and 13. The rotating plate 12 has a plurality of paddles 16 spaced radially outwardly from the outer periphery 17 of the plate 12. It will be evident that as the grinding plate 12 rotates by application of driving means to the belt pulley 9, the integral paddles 16 also will rotate. The paddles 16 extend inwardly beyond a juncture 18 of the plates 12 and 13 and thus are adapted to receive material being ground by the plates and thrown centrifugally outwardly at this circular juncture 18. An internal housing or partition 19 surrounds the revolving plate 12 and its integral paddles 16, and, as best shown in Figure 1, the housing 19 has an aperture 21 adjacent a vertical auger 22.

The vertical auger 22 is enclosed within a tubu-

lar housing 23 having an aperture coextensive with the aperture 21 of the housing 19 at its lower end thereof. The tubular housing 23 is supplied with an exit opening 24 at the top thereof of which is adjacent the spout 8. As best shown in Figure 2, the plate mill is supplied with an auxiliary shaft 26 journaled within the housing 7 and running parallel with the main driving shaft 11. Mounted on the auxiliary shaft 26 are V-belt pulleys 27 and 28. A V-belt pulley 29 keyed to the main driving shaft 11 is in alignment with the V-belt pulley 27 on the auxiliary shaft 26, and by means of a belt 31, imparts rotation from the main shaft 11 to the auxiliary shaft 26.

The vertical auger 22 comprises a central shaft 32, and a screw-type flighting 33 is wrapped around this central shaft 32 and welded or otherwise attached thereto. The vertical auger 22 has its central shaft 22 journaled within bearings 34 and 36, and at its lower end has an extension on which is mounted a V-belt pulley 36. The tubular housing 23 and the bearing 34 are supported by a bracket 37, which is attached at 38 to the housing 7. An annular flange 39 on the auger shaft 32 is positioned immediately above the bearing 34, and it is quite evident that the bearing maintains the shaft and auger 22 in their proper vertical position. Directly above the flange 39 lies a disk member 41 which forms 30 the bottom of the tubular housing 23 in so far as it concerns the auger 22.

A V-belt 42 extends between the V-belt pulleys 28 and 36 and causes rotation of the auger 22 within the tubular housing 23. An arrow 43 35 indicates the direction of rotation of the auger. As material is thrown centrifugally outwardly between the grinding plates 12 and 13, it comes within the path of the fan-like blades or paddles 16 and is thrown toward the vertical elevator in the form of the auger 22 because of the counter-clockwise rotation of the plate 12, as shown by an arrow 44 in Figure 1.

As best shown in Figure 2, the position of the vertical auger is slightly offset from a centerline or plane vertically passed through the paddles 16. The shaft 32 substantially divides the flighting 33 into proximate and remote sections. An angularly disposed conduit 46 extends between the housing 19 and the vertical housing 23 and 45 causes the material thrown from the paddle 16 to be directed toward the proximate section of the flighting 33, and inasmuch as the auger is rotated in a counter-clockwise direction, as viewed in Figure 2, the ground material is adapt- 60 ed to be scooped up and carried upwardly within

the tubular housing 23. This particular positioning of the vertical auger with respect to the vertical plane passed through the blades or paddles 16 prevents any undue agitation such as would be caused if the material was fed broadside to the entire auger. Under such circumstances a section of the auger would be repelling the material fed thereto, and the remaining section of the auger would be accepting the material received and congestion would undoubtedly be created. It is quite important, therefore, that the material delivered by the paddles 16 to the auger 22 be delivered in such a manner that the lower section of the auger flighting 33 receives all the material, and the direction of rotation of the auger will cause all the material received to be accepted by the auger and elevated in a smooth continuous manner. The feeding of the ground material to the exposed section of the auger flighting turning upwardly improves the action of the auger, and the material is lifted without undue agitation of the newly ground material.

The discharge spout 8 is relatively broad and in the central portion thereof has a rod 47 journaled within its upper and lower portions and is inclined so that the lower end of the rod 47 is directed toward the housing 7 of the grinding mill. A diverter valve or paddle 48 is fixedly attached to the rod 47 and is capable of shifting within the aperture 24 at the upper end of the tubular housing 23. The lower end of the spout 8 is divided into two sections by means of a partition 49, and movement of the valve 48, by means of a handle 51 mounted on top of the spout 8, will effect a discharge of the ground material into either one of the lower spout sections 52 or 53. As best shown in Figure 2, movement of the handle 51 in a downward direction causes the valve or divider blade 48 to be moved upwardly and abut an extension 54 of the tubu-

lar housing 23, and thereupon ground material being elevated by the auger 22 will be caused to exit through the spout portion 53. If, however, the handle had been moved upwardly, the valve 48 would contact the lower side of the tubular housing extension 54, and ground material would be diverted to the spout section 52.

It will be evident that herein is provided a novel grinding mill which incorporates several important features to contribute to an efficiently operating mill. Numerous details of construction may be changed throughout a wide range without departing from the principles disclosed herein, and it is the intention that the patent be limited only by the scope of the appended claim.

What is claimed is:

In a grinding mill comprising a rotary disc-like grinding member, blades projecting from the outer periphery of said grinding member, and a rotating auger positioned vertically and proximate an edge of said disc-like grinding member and in offset relation from said blades, said vertical auger having a central axial shaft around which auger flights are wrapped, one side of said auger flight advancing toward said grinding member and the other side of said auger flight retreating from said grinding member, an enclosed passage between said blades and the lower retreating portion of said vertical auger flight for directing ground material to that half of the auger flight which is retreating from said grinding member, whereby ground material is thrown by the blades through the passage to the retreating portion of the vertically positioned auger for quick and conducive reception of the material being ground, and a discharge spout at the top of said auger.

JOHN R. HALL.
